UNITED STATES PATENT OFFICE

HERMAN F. VOSHARDT, OF CHICAGO, ILLINOIS, ASSIGNOR TO FRIEDELEY-VOSHARDT CO., OF CHICAGO, ILLINOIS, A CORPORATION OF ILLINOIS

DESIGN FOR A CASING FOR A DISHWASHER

Application filed February 20, 1929. Serial No. 30,147. Term of patent 7 years.

To all whom it may concern:

Be it known that I, HERMAN F. VOSHARDT, a citizen of the United States, residing at Chicago, county of Cook, and State of Illinois, have invented a new, original, and ornamental Design for a Casing for a Dishwasher, of which the following is a specification, reference being had to the accompanying drawing, forming part thereof, in which the figure is a perspective view of a casing for a dishwasher showing my new design.

I claim:

The ornamental design for a casing for a dishwasher, as shown.

HERMAN F. VOSHARDT.
